(57) **CLAIM**

The ornamental design for a prismatic scope, as shown and described.

DESCRIPTION

FIG. 1 is a perspective view of a prismatic scope showing our new design.

FIG. 2 is a front view of the prismatic scope.

FIG. 3 is a rear view of the prismatic scope.

FIG. 4 is a left view of the prismatic scope.

FIG. 5 is a right view of the prismatic scope.

FIG. 6 is a top view of the prismatic scope.

FIG. 7 is a bottom view of the prismatic scope.

FIG. 8 is a perspective view of the prismatic scope, illustrating a first type of reflex sight being detachably mounted onto the prismatic scope; and,

FIG. 9 is a perspective view of the prismatic scope, illustrating a second type of reflex sight being detachably mounted onto the prismatic scope.

The broken line portion of the figure drawings is included to show unclaimed subject matter only and forms no part of the claimed design.
